(57) **CLAIM**

The ornamental design for a vehicle as shown and described.

DESCRIPTION

FIG. 1 is a front and left side perspective view of a vehicle showing our new design;

FIG. 2 is a rear and right side perspective thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The ornamental design that is claimed is shown in solid lines in the figures. The broken lines in the drawings illustrate portions of the vehicle that form no part of the claimed design. The dot-dash broken lines denote boundaries and do not illustrate structures or subject matters.
